CLAIM

The ornamental design for an inflator pump, as shown and described.

DESCRIPTION

FIG. 1 is a front, right, and top perspective view of an inflator pump, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a side wall; and,

FIG. 10 is a partial enlarged view of an area labeled 10 in FIG. 2 comprising a mesh.

The dash-dash lines shown in the drawings are included for the purpose of illustrating portions of the inflator pump that form no part of the claimed design. The short dash, long dash, short dash lines on FIGS. 1, 2, 9 and 10 depict the bounds of the region taken from FIGS. 1 and 2 to be enlarged on FIGS. 9 and 10 and form no part of the claimed design.
